UNITED STATES PATENT OFFICE.

HARRY E. HINES, OF DETROIT, MICHIGAN.

RIFLE.

1,376,694.

Specification of Letters Patent.

Patented May 3, 1921.

Application filed May 19, 1919. Serial No. 298,017.

To all whom it may concern:

Be it known that I, HARRY E. HINES, a citizen of the United States of America, residing at Detroit, in the county of Wayne 5 and State of Michigan, have invented certain new and useful Improvements in Rifles, of which the following is a specification, reference being had therein to the accompanying drawings.

10 This invention relates to that class of automatic rifles commonly styled "magazine" or "repeating" rifles, and a fire arm in accordance with my invention may be characterized in the following particulars.

15 First, the rifle has a detachable barrel that may be easily and quickly detached to reduce the longitudinal dimension of the rifle so that it may be conveniently carried, particularly in a rifle case.

20 Second, the rifle has a novel magazine positioned at the side of the trigger guard, so that cartridges may be at all times positioned to enter the breech piece and the cartridge chamber of the rifle barrel. The 25 location of the magazine is such that it may serve as an auxiliary guard for the trigger, and this arrangement is in contradistinction to the usual location of the magazine, either along the rifle barrel or behind or in 30 front of the trigger guard. The location of the magazine is such as to provide a perfectly balanced gun and the magazine may be in the form of an endless belt, cartridge carrier, or other member by which car-

35 tridges may be expeditiously carried into action, particularly when the rifle is constructed as a rapid fire implement.

Third, the rifle includes a novel re-loading mechanism that may be operated by hand or 40 by a pressure of gas produced by the firing of the rifle. The pneumatic means employed for actuating the loading mechanism is constantly articulated therewith so that it may be used, particularly after the 45 first cartridge has been placed in the cartridge chamber. The hand operating means is also in position to serve the re-loading mechanism should the pneumatic means fail, and both the hand and pneumatic means 50 are compactly assembled in the breech piece and stock and barrel grip. As brought out in my companion application filed May 19, 1919, Serial No. 298,016, the pneumatic means is in proximity to the breech piece 55 and does not overbalance the rifle.

Fourth, my invention is characterized by

a rifle wherein the parts are constructed with a view of reducing the cost of manufacture and at the same time retain those features by which safety, durability and 60 ease of assembling are secured. With such ends in view, my invention resides in the novel construction, combination and arrangement of parts to be hereinafter described and then claimed, and reference will 65 now be had to the drawings, wherein

Figure 1 is a longitudinal, vertical sectional view of a portion of a rifle in accordance with my invention, showing a cartridge in position to be fired and the rifle 70 cocked;

Fig. 2 is a longitudinal horizontal sectional view on the line II-II of Fig. 1;

Fig. 3 is a view similar to Fig. 1 showing the re-loading mechanism in a retracted position about ready to place a cartridge in 75 the cartridge chamber;

Fig. 4 is a longitudinal horizontal sectional view of the same;

Fig. 5 is a cross sectional view taken on 80 the line V-V of Fig. 1;

Fig. 6 is a side elevation of the breech piece, showing the magazine holder, partly broken away and partly in section;

Fig. 7 is a perspective view of a detached 85 loaded magazine;

Fig. 8 is a perspective view of the outer or forward end of the breech piece;

Fig. 9 is a similar view of the inner or rear end of the barrel;

Fig. 10 is a perspective view of the forward or outer end of a re-loading member, and

Fig. 11 is a cross-sectional view taken on 95 the line XI-XI of Fig. 1.

In describing my invention by aid of the drawings above referred to, I desire to point out that the same are intended as merely illustrative of the rifle which I have constructed, tested and found satisfactory, 100 therefore I do not care to confine my invention to the precise construction and arrangement of parts shown, other than what may be defined in the appended claims.

In the drawings, the reference numeral 105 1 denotes a breech piece which has the rear portion thereof terminating in a hollow stock grip into which is fitted and suitably secured a stock 3. The forward end of the breech piece 1 is adapted to be closed 110 by the inner end of a barrel 4 and an end wall 5 carried thereby. The end wall 5 is

set in from the extreme inner end of the barrel 4 and the extreme inner end of said barrel is exteriorly screwthreaded, as at 6, so that it may be screwed into a socket 7 5 provided therefor in the breech piece 1. The inner end of the barrel 4 is also formed with a cartridge chamber 8 communicating with the barrel bore 9 and said cartridge chamber is adapted to receive a cartridge 10 having a projectile 11. On the inner end 10 of the barrel 4, at the end wall 5, is a barrel grip member 12, containing a cylinder 13 for a reciprocable piston 14 which extends into the breech piece 1 below the socket 7 15 of said breech piece. The cylinder 13 and its piston 14 constitutes a portion of pneumatic means employed for actuating a re-loading member or breech block within the breech piece 1 of the rifle, said cylinder receiving gas under pressure from the bore 9 of the barrel 4, when the projectile 11 is discharged, and in this manner actuating the piston 14 in one direction to impart a retractile movement to re-loading mechanism within the breech piece 1. 20

Engaging the cap or rim 15 of the cartridge 10 is a movable or reciprocable loading member or breech block 16, which is slideable in the upper portion of the breech piece 30 1 and is adapted to have its inner or rear end engage an abutment 17 of the breech piece, said abutment receiving any end thrust of the re-loading member. The greater part of the re-loading member is recessed or cut away, as best shown in Fig. 2. On one side of the re-loading member is a recess 18 for a pivoted resilient cartridge gripping member 19, and slideable in the opposite side of the member 16 is a cartridge 35 moving member 20. The member 19 overhangs the cap or rim 15 of the cartridge and the member 20 extends to the side of the rim, so that when the member 16 is retracted the cartridge 10 may be extracted and ejected 40 from the chamber 8. The member 20 has a pin and slot connection with the member 16, as at 21, and the inner end of said member is normally engaged by a spring pressed 45 plunger 22 within the member 16 which tends to tilt the member 20, as shown by dotted lines in Fig. 4 of the drawing. The member 20 is normally held against a tilting movement by the rear end of the moving member 20 engaging in a groove 23 at the 50 side of the re-loading member 16.

When the re-loading member 16 is retracting, the cartridge moving member 20 is held stationary by means of the empty shell, which presses on an ejector 24 which engages the member 20 holding it in a rearward position until the forward end of the shell is leaving the cartridge chamber 8, at which time the spring pressure upon the cartridge moving member 20, forces the 60 member 24 against rearward end of car-

tridge opposite the gripping member 19, which causes the cartridge to be flipped outwardly and ejected from an exit 25 in the breech piece. Now the cartridge moving member 20 and the ejector 24 having been 70 partially retracted, the member 20 is out of the groove 23 and the spring pressure upon rear end of member 20 causes the forward end of the member 20 to be thrust outward against cartridge in magazine and as the 75 member 16 moves to a full retracted position, the member 20 passes by the cartridge in magazine and is released for further lateral or outward thrust as shown in Fig. 4.

The ejector or deflecting pin 24 is slideable 80 in the member 16 and loosely connected to the member 20, and slideable in the forward end of the re-loading member 16 is a firing pin 26 held against accidental displacement by a pin or screw 27. The firing pin is located for center fire relative to the cap or rim 15 of the cartridge 10. 85

As before stated, the greater part of the loading member 16 is hollow and consequently provides clearance for a hammer 90 28 adapted to be swung upwardly in the re-loading member 16 to impinge against the firing pin 26 and cause said pin to detonate the charge within the cartridge case 10. The hammer 28 is pivotally supported, as at 29, 95 in the lower portion of the breech piece 1 and the pivoted end of said hammer has a crank portion 30 provided with an anti-frictional roller 31 engaged by the end of a comparatively flat slotted main spring 32 extending into the stock grip 2 and connected thereto, as at 33. The hammer 28 has its head or outer end extending through the slot 34 of the main spring 32 and provided with notches or shoulders 35 and 36 adapted to be alternately engaged by the shoulders 37 and 38, respectively, of a trigger 39 pivotally held, as at 40, in the lower portion of the breech piece 1 and extending into a trigger guard 41 of said breech piece. The trigger 110 39 has a finger piece 42 and a lug or projection 43 normally engaged by a spring 44 held by the same fastening means 33 as the main spring 32. The force produced by the spring 44 is adapted to maintain the trigger 39 115 normally in engagement with the hammer 28, so that said hammer will be held fully cocked. As shown in Fig. 1, the hammer is 120 fully cocked and when the finger piece 42 is pulled the hammer 28 is released and the expansive force of the spring 32 projects the head or outer end of the hammer upwardly into the re-loading member to strike the firing pin 26. When the hammer 28 is restored to normal position, as will hereinafter appear, the shoulder 37 of the trigger 39 engages in the notch 35 of the hammer 28 and the hammer is held even should the user of the rifle maintain finger pressure on the trigger. 125 When the trigger is released, the 130

shoulder 37 is moved out of engagement with the notch 35 and the shoulder 38 placed in engagement with the notch 36 of the hammer whereby the hammer is fully cocked 5 and any pulling movement of the finger piece 42 completely releases said hammer. The initial engagement between the hammer and trigger is essential to prevent repeated firing, without trigger action, or misplacement of the hammer while the reloading member is retracted.

Pivots connected to the rear end of the re-loading member 16, as at 45, is a latch 46 adapted to be engaged by the head 47 of the 15 reciprocal member 48 pivotally connected to the rear end of the piston 14, as at 49, said reciprocal member being slotted to provide clearance for the hammer 28 and also provided with an inclined portion 50 20 adapted to engage the hammer 28 and shift said hammer to a cocked or normal position. When the piston 14 imparts movement to the reciprocal member 48, the head 47 of said member engages the latch 46 with a wedging 25 action and shifts said latch against the abutment 17 which serves as a fulcrum for said latch, causing the latch to be rocked to lower the rear end of the re-loading member 16 out of engagement with the abutment 17, 30 whereby the re-loading member may be carried into the stock grip 2 by the head 47 remaining in engagement with the latch 46, and assume the position shown in Fig. 3.

Pivots connected to the head 47 of the 35 reciprocal member 48 by a pin 51 or other pivotal means is a retracting member 52 which engages a spring pressed plunger 53 slidable in a cylinder 54 mounted in the stock 3 of the rifle, said plunger being engaged by 40 a coiled spring 80 within the cylinder. The forward end of the retracting member 52 has a hookshaped portion 55 slidable in a guide 56 within the stock grip 2, said guide having its rear end supporting the forward 45 end of the cylinder member 4 and connected to the stock grip 2, as at 57, and its forward end provided with shoulders 81 on which bears the head 47 of the reciprocal member 48, when holding the re-loading member 16 50 against the abutment 17. In this manner the re-loading member 16 is firmly braced during the firing of a cartridge. The hookshaped portion 55 of the retracting member 52 is adapted to be engaged by a finger 58 55 slidable in a slot 59 of the stock grip 2, and said finger is connected to a slide 60 slidable on a dove-tailed tongue 61 of the stock grip 2. The slide 60 normally closes the slot 59, as best shown in Fig. 1, and the forward end 60 of said slide has a finger grip 62, so that the slide can be gripped and retracted to impart a similar movement to the retracting member 52. The connection between the finger 58 and the hookshaped portion 55 of 65 the retracting member 52 is such that the

retracting member 52 may be actuated by the pneumatic means through the medium of the reciprocable member 48, independent of the hand operating means represented by the elements 58, 60 and 62.

70

That side of the breech piece 1, opposite the exit 25, has an integral housing 63 with the bottom of said housing open so that a magazine casing 64 may have its upper end pushed upwardly into the housing, and said magazine assumes a position in parallelism with the vertical plane passing through the axis of the breech piece, as best shown in Fig. 5. The magazine when in position closes what might be considered the left-hand side of the trigger guard 41 and is adapted to contain cartridges which are elevated by the expansive force of a spring 65 located in the closed lower end or bottom of the magazine 64. The upper end of the 85 magazine 64 has an oblong opening 66 confronting the re-loading member 16 and communicating with the interior of the breech piece 1. The opening 66 is of such shape that the cartridges may be manually placed 90 in the magazine to load the same, and the cartridges automatically removed from said magazine. One end of the opening 66 exposes the cap or rim 15 of the uppermost cartridges 10 and the opposite end of the 95 opening 66 exposes the end of the projectile 11 of the uppermost cartridge.

When the re-loading member 16 is restored to normal position by the expansive force of the spring 80 behind the plunger 53 100 in the cylinder 54, the cartridge moving member 20, which is in a tilted position, as shown in Fig. 4, engages the cap or rim 15 of the cartridge 10 within the magazine and forces the cartridge forward so that the projectile 11 of the cartridge rides against the beveled wall 67 of the breech piece 1, said wall deflecting the end of the cartridge into the cartridge chamber 8, and further movement of the cartridge by the re-loading 105 member 16 causes the cartridge to be pushed home into the position in Fig. 2. During this operation the cartridge moving member 20 is behind the cartridge and as the cartridge is seated, the member 20 is straightened and held while the re-loading member 16 abuts the cartridge 10; the rear end of the member 20 extending into the groove 23 to hold said member as shown in Fig. 2. It is also during this operation that the cartridges remaining in the magazine 64 crowd the uppermost cartridge into an active position in the magazine, and this operation may be repeated until the magazine 115 is exhausted.

To retain the magazine 64 in engagement with the housing 63, an end wall of said housing has a resilient detent 68 adapted to snap into an opening 69 in the magazine 64 and support said magazine within its hous- 130

125

ing until the detent is manually actuated to release the magazine.

The rifle possesses certain other refinements, for instance, at the connection between the barrel 4 and the breech piece 1. The end wall 5 and the breech piece 1 are constructed to provide a tongue 70 adapted to interlock in a groove 71, and after such interlocking connection a screw 72 may be 10 mounted in the breech piece 1, as shown in Fig. 4, to hold the barrel 4 against accidental rotation relative to the breech piece. The screw threaded connection between the barrel 4 and the breech piece 1 is such that 15 a single or partial rotation of the barrel is sufficient to place the tongue and groove in active relation.

Another refinement of the rifle is a safety device adjacent the trigger 39, said safety 20 device consisting of a rock shaft 73 held in adjusted position by a spring 74 mounted within the stock grip 2. The rock shaft 73 is adapted to engage the trigger 39 and prevent the finger piece 42 from being pulled. One end of the rock shaft 73 has a 25 crank 75 which permits of the rock shaft being manually adjusted. The lowered position of the crank 75 indicates that the trigger is locked and the upper portion of 30 the crank indicates that the trigger is free, and with said crank adjacent and parallel to the finger piece 42, the user of the rifle can determine the condition of the safety lock by the finger and thus reduce the 35 chances of accidentally discharging the rifle.

Another refinement is that of a locking device 76, at the side of the breech piece 1 to hold the piston 14 in a retracted position, 40 so that the barrel 4 may be removed from the breech piece. This locking device is best shown in Fig. 4 and may be in the form of a resilient member actuated by a button.

Assuming that the rifle is in position for 45 firing, as shown in Fig. 1, a pull on the trigger 42 releases the hammer 28 and the cartridge 10 is detonated. As the projectile 11 goes forward in the bore 9 of the barrel 4, the pressure of gas behind the 50 projectile and against the piston 14 forces the reciprocable member 48 rearwardly until its head 47 engages the latch 46 and retracts the re-loading member 16 causing the re-loading member to extract the cartridge 55 case 10 and eject it at the exit 25. As the re-loading member 16 moves rearwardly, the retracting member 52 enters the cylinder 54, placing the spring 80 therein under tension, and this is accomplished without interfering with the normal condition of the 60 finger 58. At the completion of the rearward stroke of the re-loading member 16, the expansive force of the spring 80 within the cylinder 54 shifts the retracting member 52 and re-loading member 16 forward to

normal position, and as this is accomplished another cartridge is removed from the magazine 64 and injected into the cartridge chamber 8 of the barrel 4.

The retractile movement of the reciprocatory member 48 has reset the hammer 28 and the gun may be again fired. This operation may be repeated until the magazine is exhausted, at which time the magazine may be quickly removed, reloaded, or a 70 loaded magazine substituted for the empty magazine.

From the foregoing it will be observed that the pneumatic means employed for retracting the reloading member 16 is independent of the hand operated means but that the hand operated means is at all times in position and condition so that the reloading member 16 may be retracted by hand. When the pneumatic means is employed for 80 reloading purposes, the rifle has a shorter range than if the reloading is attained by hand, since the gas pressure behind the projectile is reduced, as brought out in my companion application.

Another important feature is that of feeding the cartridges sidewise in position to enter a cartridge chamber, instead of from below or above, so with this end in view, it is possible to locate the magazine at either 90 side of the breech piece in the rear or at the front of the trigger guard whereby a cartridge may have a lateral movement toward the cartridge chamber. For some rifles or guns it may be necessary to locate the magazine so that it will not interfere with a left 95 hand operation of the trigger.

What I claim is:—

1. A rifle comprising a breech piece having a trigger finger piece guard, a barrel having a cartridge chamber, a magazine at the side of said breech piece and closing one side of the trigger finger piece guard, and a reciprocable re-loading member in said breech piece adapted to force a cartridge in 105 a horizontal plane out of said magazine into the cartridge chamber of said barrel.

2. A rifle as characterized in claim 1, wherein the magazine has a side opening communicating with the breech piece and 110 said breech piece has a normally closed top and a side exit opening opposite said magazine.

3. A rifle as characterized in claim 1, wherein the re-loading member is spring actuated in one direction and hand operated in the opposite direction.

4. A rifle comprising a breech piece having a trigger finger piece guard, a barrel having a cartridge chamber, cartridge 125 holding means at one side of said breech piece and closing one side of the trigger finger piece guard thereof, and reciprocable means in said breech piece adapted to engage the rear end of the cartridge and force it 130

laterally endwise out of the cartridge holding means into the cartridge chamber of said barrel.

5. A rifle comprising a breech piece having a trigger finger piece guard, a detachable barrel having a cartridge chamber, a detachable magazine at the side of said breech piece closing one side of the trigger finger piece guard thereof and having a side opening into said breech piece and adapted to expose the side of a cartridge in said breech piece, a reciprocable re-loading member in said breech piece, a cartridge gripping member carried by one side of said re-loading member, a cartridge moving member carried by the opposite side of said re-loading member adapted to engage the cap of a cartridge exposed by the magazine and shift it laterally out of the magazine into the barrel chamber, and means adapted to reciprocate said re-loading member so that the cartridge moving member may shift the cartridge into the barrel chamber and the cartridge gripping member extract the cartridge shell therefrom, the cartridge moving member acting while the cartridge gripping member is stationary.

6. A rifle as characterized in claim 5 wherein the reciprocating means of said re-loading member is spring actuated in one direction and actuated in the opposite direction by gas pressure from the rifle barrel.

7. A rifle comprising a barrel having a cartridge chamber, a breech piece having a normally closed top and a normally open exit at one side thereof, a magazine at the opposite side of said breech piece adapted to expose a cartridge at the side of the breech piece, a reciprocable re-loading member in said breech piece, a cartridge gripping member in one side of said reciprocable re-loading member, a cartridge moving member in the opposite side of said reciprocable reloading member adapted to engage the cap of a cartridge and shift the cartridge into the chamber of said barrel and into engagement with the cartridge gripping member of said reciprocable re-loading member, an ejector carried by the cartridge moving member of said reciprocable reloading member and adapted to cooperate with said gripping member in ejecting a cartridge shell laterally from the exit of said breech piece, and means adapted for reciprocating said re-loading member.

8. A rifle as characterized in claim 7 wherein the reciprocating means of said re-loading member is spring actuated in one direction and hand operated in the opposite direction.

9. A rifle as characterized in claim 7 wherein the reciprocating means of said re-loading member is spring actuated in one direction and actuated in an opposite direction by gas pressure from the rifle barrel.

10. In a rifle, the combination of a breech piece having a trigger finger piece guard, a barrel attached thereto provided with a cartridge chamber, a magazine at the side of said breech piece and closing one side of the trigger finger piece guard, a re-loading member in said breech piece adapted to obtain a cartridge from said magazine and shift it into said barrel chamber, an abutment forming part of said breech piece adapted to be engaged by said re-loading member, a reciprocable member below said re-loading member and having a head adapted to hold said re-loading member in engagement with said abutment, a latch carried by said re-loading member and adapted to be engaged by the head of said reciprocable member to shift said latch against said abutment and lower the end of said re-loading member so that said reciprocable member may retract said re-loading member, means adapted to shift said reciprocable member to retract said re-loading member, and means adapted to restore said re-loading member to normal position in said breech piece.

11. The combination set forth in claim 10 wherein a cartridge firing mechanism operates through said reciprocable member.

12. The combination set forth in claim 10 wherein the restoring means of said re-loading member includes a spring acting through the head of said reciprocable member to maintain the head against the inner end of the re-loading member and said member against the breech piece so that it may be pushed forwardly in the breech piece.

13. In an automatic repeating rifle, a re-loading member, a reciprocable member below said re-loading member adapted to retract said re-loading member to extract a cartridge case from the rifle, means adapted to utilize gas pressure from the rifle to move said reciprocable member in one direction, a hammer pivoted below said reciprocable member and having a head adapted to extend through said reciprocable member and enter said re-loading member to fire a cartridge and be reset during a retractile movement of said re-loading member, and a trigger pivoted in the rear of said hammer having two independent engagements with the head of said hammer to retain said hammer reset.

14. An automatic repeating rifle as characterized in claim 13 wherein a rock shaft is associated with said trigger to engage the trigger and hold it against actuation, and an operating crank on said rock shaft disposed to extend parallel to said trigger and be engaged by the same finger as the trigger.

15. In an automatic repeating rifle, a breech piece, a barrel carried by said breech piece and providing a cartridge chamber, a

magazine at the side of said breech piece, a re-loading member in said breech piece, adapted to transfer a cartridge from said magazine to said barrel chamber, a pivoted latch carried by said re-loading member, a reciprocable member in said breech piece adapted for engagement with the latch of said re-loading member to move said re-loading member in one direction to extract

10 the cartridge case from the barrel chamber, a retracting member pivotally connected to said reciprocable member, and means associated with said retracting member adapted to move said re-loading member in an opposite direction when said reciprocable

15 member actuates said re-loading member so

that a cartridge may be transferred from the magazine to the barrel chamber, and manually actuated means adapted for connection with said retracting member to retract said member.

16. An automatic repeating rifle as characterized in claim 15 wherein gas pressure operated means is connected to said reciprocable member to retract said member independently of said manually actuated means.

In testimony whereof I affix my signature in the presence of two witnesses.

HARRY E. HINES.
